SIGNALLING SYSTEM FOR SIMULTANEOUSLY TRANSMITTING A PLURALITY OF MESSAGES

Kurt Hagenhaus, Berlin-Siemensstadt, Germany, assignor to Siemens & Halske Aktiengesellschaft, Munich, Germany, a corporation of Germany

Application February 20, 1953, Serial No. 338,112

Claims priority, application Germany March 11, 1952

8 Claims. (Cl. 179—15)

This invention relates to the transmission of messages in signalling systems and is particularly concerned with circuit arrangements for substantially simultaneously transmitting a plurality of telephone messages over a common transmission or connecting channel.

In order to transmit a plurality of messages practically simultaneously over a common transmission channel which may extend over physical lines or which may be built up wireless by employing a high frequency carrier, pulses are used for each message which recur in certain rhythm or periodic sequence and which are modulated by the corresponding message, e. g., as to amplitude. Interspersed with the recurring pulses of one message but displaced relative as to time are the modulated pulses of another practically simultaneously transmitted message which recur in the same periodic sequence or rhythm as the pulses of the first message. Each sequence of pulses recurring in the same rhythm therefore forms a transmission or message channel.

For example, if it is assumed that 100 subscribers' lines have access to such a common transmission channel, there will be required 100 pulses each of which may be associated, e. g., with one of the 100 subscribers' lines. Each pulse serves in such a case incident to its periodic transmission for forming one transmission channel, resulting in 100 channels. If all the subscribers should happen to be engaged in calls, 100 pulses will be successively transmitted over the common channel, and these pulses, the duration of which may be shortened will thereafter be repeatedly transmitted in the same rhythm for the duration of the calls. Each individual pulse is in such a case a carrier for portions of its corresponding message due to modulation thereof by such message.

The called subscribers' lines which are to receive the individual messages are connected to the common transmission channel at the instant of receipt of the corresponding message-modulated pulses. This may be accomplished, for example, by valve devices (input gates) which are opened in step with the successively transmitted pulses assigned to the respective lines, the opening of such gates thus in a sense extracting, impulsewise, from the intermixture of messages, the individual message portions of the corresponding messages.

Since the effective power or capacity of the transmitted messages is as compared with continuous transmission considerably reduced, due to the impulsewise scanning in accordance with the scanning ratio, it is necessary to amplify the messages transmitted to the individual lines.

In order to keep the required expenditure as small as possible the invention provides a common connection stage (group connection device) for the subscribers' lines whose pulses exhibit a mutual spacing which is a multiple of the spacing of the individual pulses which are displaced or staggered as to time. This connecting device is interconnected with the common transmission channel, by such a tube circuit responsive to pulses which are modulated with message portions for the corresponding group of

2

lines. The tube circuit serves at the same time for expanding the incoming pulses and if desired for amplifying such pulses.

The invention will now be described with reference to the accompanying diagrammatic drawings wherein:

Fig. 1 shows in its top portion pulses derived from a main oscillator while the bottom portion indicates the corresponding shortened pulses;

Fig. 1a indicates a circuit for expanding the shortened derived pulses from the oscillator;

Figs. 2 to 4 illustrate circuit examples for a system having 100 subscribers' lines, Fig. 2 representing a wiring scheme for the 100 lines; Fig. 3 showing in schematic manner the electronic connection devices of the common transmission channel; and Fig. 4 illustrating a group of 100 lines with the arrangement serving for the connection thereof;

Fig. 5 indicates in diagrammatic manner a network for 1000 subscribers;

Fig. 6 shows diagrammatically a network for 1000 lines wherein the common transmission channel is formed by a selection stage; and

Figs. 6a-6d indicate modifications of the structural features of the selection stage.

Referring now to Fig. 1, a suitable generator or oscillator is used which delivers a certain frequency (e. g., 10 kc.) from which are derived in periodic sequence 100 pulses $P_{11} \dots P_{00}$. These pulses are, for example, transmitted during a time of 100 μ sec. Each pulse is transmitted for a duration of 5 μ sec. and the pulses therefore partially overlap as indicated in connection with the pulses $P_{11} \dots P_{21}$. The leading flanks of the pulses are spaced by 1 μ sec. The leading flanks of the pulses P_{11}, P_{21}, P_{31} , etc. to P_{01} are always spaced by 10 μ sec. The pulses $P_{22} \dots P_{20}, P_{32} \dots P_{30}$, etc. have been omitted to simplify representation. The leading flanks are, as indicated, between the leading flanks of the pulses $P_{21} \dots P_{31}, P_{31} \dots P_{41}$ and so forth.

The pulses $P_{11} \dots P_{00}$ are respectively associated with individual subscriber's lines such as the lines $T_{n_{10}} \dots T_{n_{00}}$ indicated in Fig. 2. They are made effective, for serving in the connection of a desired line, in accordance with a certain grouping scheme which will be explained presently.

The pulses $P_{11} \dots P_{00}$ of approximately 5 μ sec. duration are by differentiation shortened, resulting in the sequence shown in the lower part of Fig. 1 at $P'_{11} \dots P'_{00}$. These pulses have been shortened to 0.5 μ sec. and therefore do not overlap. The shortened pulses $P'_{11} \dots P'_{00}$ need not lie, as indicated in Fig. 1 and as seen in point of occurrence at the leading flanks of the pulses $P_{11} \dots P_{00}$ but may lie midway of such pulses. The advantage which is thereby obtained is, that time and phase variations are not detrimental to extracting from the pulses the corresponding portions of the messages. The significance of the shortening of the pulses will be explained presently.

The arrangement may also be formed so that the shortened pulses $P'_{11} \dots P'_{00}$ are derived from the pulses of the main oscillator and are thereafter transformed into the pulses $P_{11} \dots P_{00}$ by expansion thereof, e. g., by means of a device as indicated in Fig. 1a.

Referring to Fig. 1a, one of the pulses $P'_{11} \dots P'_{00}$ of 0.5 μ sec. duration, indicated in simplified manner by P' (0.5 μ s.) reaches the grid of the tube R_0 . At the cathode resistor R_k this pulse will appear in its original form, but with a gain in power. The capacitors C_1, C_2 and C_3 are simultaneously charged over the capacitor C_0 and the rectifiers G_{11}, G_{12} and G_{13} . The capacitor C_0 is thereby likewise charged, such that its coating which faces the cathode becomes positive. All capacitors are thus charged at the conclusion of the pulse. The undesired charge of

the capacitor C_0 is discharged through the rectifier Gl_0 . The capacitors $C_1 \dots C_3$ cannot discharge through the rectifiers $Gl_1 \dots Gl_3$, the latter blocking the discharge. The capacitors $C_1 \dots C_3$ and the associated inductance coils $L_1 \dots L_3$ now form a circuit which is shunted at the side facing the tube Ro causing a discharge which increases the effect. The charges are dissipated toward the output side and result in the expanded pulse P of 5 μ sec. duration as indicated at P (5 μ sec.).

As will be seen from Fig. 2, there are provided 100 subscribers' lines $Tn_{11} \dots Tn_{00}$. In the example shown, there are formed groups each having 10 lines. The subscribers' lines Tn_{11}, Tn_{21} and so forth to Tn_{01} have access to the group connecting device GV_1 ; the lines $Tn_{12}, Tn_{22} \dots Tn_{02}$ have access to the group connecting device GV_2 ; the lines $Tn_{16}, Tn_{26} \dots Tn_{06}$ reach the group connecting device GV_6 ; the lines $Tn_{19} \dots Tn_{09}$ reach the group connecting device GV_9 ; the lines $Tn_{10} \dots Tn_{00}$ reach the group connecting device GV_{10} .

The subscriber's line which at any time calls later is connected by its outlet gate, which is periodically opened by the pulse assigned to the respective line, with the corresponding group connecting device. Thus, the line Tn_{11} is connected with the group connecting device GV_1 over its outlet gate AT_{11} upon occurrence of the pulse P_{11} ; the line Tn_{21} (not shown) is connected by its associated similar outlet gate AT_{21} upon occurrence of the pulse P_{21} with the group connecting device GV_1 , and so forth.

It will be seen therefore that the connections of the individual subscriber's lines with the associated group connecting devices takes place at different successively occurring instances. The same is true so far as the connection of the remaining lines with the other group connecting devices is concerned.

The individual group connecting devices thus form the first connecting stage and reach over outlet gates such as $A_1 \dots A_X$, which are in each instant opened by pulses of the particular subscriber's line connected to the respective group connecting devices, a multiple V forming the second connecting stage and over this multiple they reach the inlet end ME of a multiplex device constituting the common transmission or channel. The pulses serving the opening of the outlet gates are shortened, that is, they are the differentiated pulses indicated at the bottom of Fig. 1. Their duration is 0.5 μ sec.

For example, if it is assumed that the subscriber's line or station Tn_{11} originates a call, the outlet gate AT_{11} now associated with such line is periodically or rhythmically opened by the pulses P_{11} which are individual to the calling line and the calling line Tn_{11} is correspondingly periodically connected with the group connecting device GV_1 . This group connecting device is periodically connected with the multiplex inlet ME, over the multiple V, by the shortened pulses $P'_{11} \dots P'_{01}$ corresponding to the lines $Tn_{11} \dots Tn_{01}$.

Similar operations occur responsive to a call originating, for example, at the subscriber's station Tn_{21} . Such station will be periodically connected in the same time sequence, but at different instances, by means of the pulse P_{21} associated therewith, over a similar outlet gate (not shown), with the group connecting device GV_1 and the latter will be periodically connected with the inlet of the multiplex device ME over the outlet gate A_1 and the multiple V.

Each calling line is operatively connected with the multiplex device by a connecting device. For example, the line Tn_{11} which has been assumed to have called first, will connect with the connecting device VE_1 . The connecting device VE_1 is effected in a manner to be described presently, by the dial pulses from the calling line which designate the called line, for example, line Tn_{10} (the previously mentioned pulses serving as a carrier for the dial pulses) so as to produce a pulse transformation corresponding to the called line. It causes transmission of the pulse P'_{10} associated with the called line which has

been shortened (0.5 μ sec.), from the multiplex outlet MA over the multiple V to the inlet gate $E_1 \dots E_X$. Of these inlet gates, only the gate E_X will switch through to the group connecting device GV_{10} , responsive to receipt of the pulses P'_{10} due to circuit means which will be explained presently. The pulses P_{10} (5 μ sec. duration) which are associated with the called line Tn_{10} are also transmitted to the inlet gate ET_{10} and the latter is accordingly periodically opened. Therefore, when the shortened pulse P'_{10} (0.5 μ sec.) opens the inlet gate E_X , the inlet gate ET_{10} will be simultaneously opened by the unaltered or non-shortened pulse P_{10} (5 μ sec.). The inlet gate ET_{10} therefore is opened for a longer interval (non-shortened pulse P_{10}) than the gate E_X . The pulse P'_{10} received by the inlet gate E_X which has a duration of about 0.5 μ sec. and which has been modulated by part of the message is expanded by a device shown in Fig. 4, which will be described later on, which is associated with the group connecting device GV_1 , and is if desired subsequently amplified. Costly amplifiers at the individual subscribers' lines are avoided by the power increase obtained by the expansion of the pulses. If the transmitted power does not suffice, the subscriber's station may be provided with semi-conductor amplifiers of the transistor type or with simple amplifier tubes.

In order to carry out the above indicated expansion of the message-carrying pulses, the various subscribers' lines are grouped so that they are always on a group connecting device whose associated pulses exhibit a spacing which exceeds that of the expanded pulse. In the assumed example, those lines are connected with the same group connecting device whose pulses referred to the leading pulse flanks exhibit a spacing of 10 μ sec. Accordingly, the lines $Tn_{11} \dots Tn_{01}$ (pulses $P_{11}, P_{21} \dots P_{01}$) are connected with the group connecting device GV_1 ; the lines $Tn_{12}, Tn_{22} \dots Tn_{02}$ (pulses $P_{12}, P_{22} \dots P_{02}$) are connected with the group connecting device GV_2 , and so forth.

The transmission of messages over the common transmission channel will now be described somewhat more in detail by explaining with reference to Fig. 4 the pulse expansion and the subsequent periodic connection of the individual subscribers' lines with their associated group connection devices.

It has been assumed that the message from the calling station Tn_{11} (Fig. 2, fork circuit G_{11}) is transmitted over the circuits for the outlet gate AT_{11} , group connecting device GV_1 , outlet gate A_1 , multiple V, multiplex inlet ME, connecting device VE_1 , multiple V, inlet gate E_X , group connecting device GV_{10} , inlet gate ET_{10} , and additional elements (low pass TP_{10} , transistor amplifier T_{10}) to the desired line Tn_{10} . The message in opposite direction, from the called station Tn_{10} to the calling station Tn_{11} is transmitted over the fork circuit G_{10} , outlet gate AT_{10} , group connecting device GV_{10} , outlet gate A_X , multiple V, multiplex inlet ME to the connecting device VE_1 . In this connecting device is obtained the transformation from the pulse P'_{10} to the pulse P'_{11} of the calling line, so that the further transmission path extends over the multiple V, inlet gate E_1 , group connecting device GV_1 , inlet gate ET_{11} , low pass TP_{11} , transistor T_{11} to the calling line Tn_{11} . The outlet gate AT_{10} is thereby periodically opened for 5 μ sec., by the non-shortened pulse P_{10} associated with the called line Tn_{10} and the outlet gate A_X is opened for shorter periods by the shortened pulse P'_{10} of 0.5 μ sec.

For the connection of the subscriber station Tn_{10} there is however available only the interval of simultaneous opening of the outlet gates AT_{10} and A_X . If there exist other calls, the outlet gate A_X will be periodically opened at other instances by the corresponding pulses, e. g., $P'_{20} \dots P'_{00}$. The outlet gates AT_{20} etc. of the other stations $Tn_{20} \dots Tn_{00}$ are periodically opened at corresponding times as soon as their pulses $P_{20} \dots P_{00}$ become effective. At the calling end (line Tn_{11}) will be

opened the inlet gate E_1 by the pulse P'_{11} —0.5 μ sec., and the inlet gate ET_{11} by the pulse P_{11} —5 μ sec. The connecting device VE_1 carries out the previously indicated transformation of the pulse P'_{11} to the pulse P'_{10} and the pulse P'_{10} to the pulse P'_{11} , respectively.

The manner in which the pulse transformation is carried out will now be explained with reference to the block diagram shown in Fig. 3.

As already mentioned, between the multiplex inlet ME and the multiplex outlet MA are disposed a number of connecting devices, two being shown in Fig. 2 at VE_1 and VE_2 , the number of such devices being in accordance with the number of simultaneous calls to be expected over the multiplex line. The connecting device, e. g., the device VE_1 comprises the elements schematically indicated in Fig. 3. There are provided two oscillators O_1 and O_2 . The frequencies of these oscillators deviate by a few cycles from the frequency of the main oscillator from which are derived the pulses $P_{11} \dots P_{00}$ as explained with reference to Fig. 1. When the pulse derived from the main oscillator and subsequently shortened (pulse P_{11} —0.5 μ sec.) appears in the multiplex input ME , responsive to a call from the subscriber station Tn_{11} , a regulating or control voltage will be produced in the pulse-phase comparator Phv_1 , at the instant of deviation existing between the pulse P_{11} and the pulse derived from the oscillator O_1 . This regulating or control voltage serves for restoring phase synchronism between the oscillator O_1 and the main oscillator (not shown) so that the pulses P'_{11} and P'_{11a} occur at the same instant. The pulse P'_{11} at the multiplex inlet ME is upon synchronizing so transformed or altered by a counter pulse from a device (not shown) that other connecting devices cannot partake in the synchronizing. The pulse P'_{11a} opens the inlet gate ET_1 in correct phase so that the low frequency message appears in the device NF_1 in back of the low pass T_1 .

The dial pulses which designate the desired subscriber cause setting of an idle phase shift device Ph which has been made available by an allotter Pz so as to derive from the oscillator O_2 the pulse P'_{10a} the phase position of which corresponds to the pulse P'_{10} , of the desired subscriber, which is derived from the main oscillator. This pulse P'_{10a} is used to transmit a ring from the pulse allotter Pz over the device NF_1 , outlet gate AT_1 , multiplex outlet MA , multiple V , inlet gate E_X , group connecting device GV_{10} , inlet gate ET_{10} , low pass TP_{10} , transistor T_{10} , fork circuit G_{10} , to the desired party Tn_{10} .

If the called party Tn_{10} answers, its pulse P_{10} will appear in back of its outlet gate AT_{10} at the group connecting device GV_{10} , which reaches the multiplex inlet ME as a shortened pulse P'_{10} over the outlet gate A_X and the multiple V . The pulse phase comparator Phv_2 now causes synchronization of the pulses P'_{10} and P'_{10a} in a similar manner as explained with reference to the pulse phase comparator Phv_1 . The phase shift device Ph which had been connected by the allotter Pz is now released.

The synchronized pulse P'_{10a} opens the outlet gate AT_1 in step with the pulses P_{10} so that the message of the party Tn_{11} is transferred from the pulse P'_{11} to the pulse P'_{10} of the desired party Tn_{10} . In the opposite direction, the inlet gate ET_1 and the outlet gate ET_{11} are respectively controlled by the pulses P'_{10a} and P'_{11a} .

Accordingly, when the party Tn_{11} calls the party Tn_{10} , the pulse P'_{11} carrying the message parts is transferred to the pulse P'_{10} while the pulse P'_{10} is transformed to the pulse P'_{11} in opposite direction from the party Tn_{10} to the party Tn_{11} . The party talking at any instant is therefore on the side of the multiplex input ME while the listening party is on the side of the multiplex output MA .

The devices disposed at the multiplex output MA so far as they concern the invention in connection with the subscriber lines Tn_{10} , $Tn_{20} \dots Tn_{00}$ are indicated in Fig. 4. If the subscriber Tn_{10} is desired, as has been

assumed, the shortened pulse P'_{10a} (0.5 μ sec.) which is modulated with the corresponding message part is periodically transmitted from the connecting device VE_1 as already explained with reference to Fig. 3. This modulated pulse appears at the inlet gates $E_1 \dots E_X$ shown in Fig. 2. However, it becomes effective only at the inlet gate E_X because only this gate receives the pulse P'_{10} derived from the main oscillator. The above indicated operations are apparent from Fig. 4 which will now be described more in detail.

As will be seen from Fig. 4, the non-shortened pulse P_{10} (5 μ sec.) derived from the main oscillator reaches the grid of the tube Ro_3 over the rectifier Gl_{10} . The pulse P_{10} is amplified and directed over the transformer Tr_2 to the differentiating element comprising the capacitor C_1 and primary winding of the transformer Tr_3 ; the differentiated pulse P_{10} (0.5 μ sec.) is derived from the secondary winding of the transformer Tr_3 and is conducted to the suppression grid of the tube Ro_1 at such a potential and in step with the pulse P'_{10} , that the tube becomes conductive, provided that its control grid receives at such instant the modulated pulse P'_{10a} from the multiplex output MA . This operation corresponds to the periodic opening of the inlet gate E_X shown in Fig. 2. The pulse P'_{10a} modulated with the corresponding message part charges the capacitor C_2 over the rectifier Gl_1 . The potential on the capacitor C_2 therefore follows the peak value of the modulated pulse P'_{10a} and therewith its modulation by the corresponding message part. The capacitor C_2 cannot discharge for the duration of 5 μ sec. after its charging interval because in its discharge path is disposed the rectifier Gl_2 as a valve carrying during this interval a blocking potential from the secondary winding of the transformer Tr_2 in accordance with the pulse P_{10} . When the blocking potential disappears at the end of the pulse P_{10} , that is, after 5 μ sec., the capacitor C_2 will discharge over the rectifier Gl_2 allowing charging again in accordance with the successive modulated pulse P'_{10a} . The modulated pulses P'_{10a} of 0.5 μ sec. duration are thus expanded to 5 μ sec.

If there are at such time connections between other lines belonging to the same group, for example, the lines $Tn_{20} \dots Tn_{00}$, there will be additionally transmitted from the multiplex outlet MA to the grid of the tube Ro_1 the correspondingly modulated pulses $P'_{20a} \dots P'_{00a}$, each of 0.5 μ sec. duration. The capacitor C_2 is thus charged and discharged in the intervals of its charging by the modulated pulse P'_{10a} thus permitting extraction of message parts belonging to the other lines. The corresponding pulses are also expanded, each to 5 μ sec. duration. Mutual disturbance or interference between the various message portions does not occur because the modulated pulses $P'_{10a} \dots P'_{00a}$ (0.5 μ sec.) which appear at the grid of the tube Ro_1 are always spaced by 10 pulses.

The individual expanded pulses appear at the grid of the tube Ro_2 where they are amplified and directed over the transformer Tr to the group connecting device GV_{10} . To this device may be connected the lines $Tn_{10}, Tn_{20} \dots Tn_{00}$ over the inlet gates $ET_{10}, ET_{20} \dots ET_{00}$ which are formed as modulators or controlled rectifiers. The modulator of the inlet gate ET_{10} is opened because the pulse P_{10} (5 μ sec.) appears simultaneously with the expanded modulated pulse P'_{10a} and the modulated amplified and expanded pulse P'_{10a} therefor can pass. The control frequency parts are filtered out in the low pass filter TP_{10} and the remaining message is conducted to the line Tn_{10} either without further amplification or over a transistor T_{10} or a suitable simple amplifying tube and over the fork circuit G_2 shown in Fig. 2. The messages for other subscribers which are connected to the group connecting device GV_{10} are similarly transmitted by the opening of the inlet gates under control of the associated non-shortened pulses responsive to simultaneous appearance of the correspondingly modulated pulses.

It will be clear from the foregoing explanations that the message from a calling line or party is conducted, first, with a pulse duration of 5 μ sec. to the associated group connecting device, e. g., GV_1 forming the first connecting stage, and second, with a shortened pulse duration of 0.5 μ sec. from the multiple V as the second connecting stage, to the tube circuit such for example as E_X , with subsequent expansion to a duration of 5 μ sec. ahead of the group connecting device, e. g., GV_{10} .

The arrangement may also provide for directly transmitting the message from the calling end with shortened pulses and to carry out the expansion of the pulses at the called end only ahead of the group connecting device, e. g. GV_{10} . If the line Tn_{11} is for example assumed to be calling, its outlet gate AT_{11} will in such a case not be periodically opened by the pulse P_{11} (5 μ sec.) but by the pulse P'_{11} (0.5 μ sec.). The expansion at the called end is then carried out as already described. Lines having associated therewith pulses which exhibit a spacing that permits such expansion may be disposed in groups and connected with the identical group connecting device which is common thereto. The expansion and amplification of the pulse is then carried out by an amplifier device in the group connecting device which is common to such a group of subscribers' lines. Costly amplifier devices for the corresponding individual lines are thus avoided.

As shown in Fig. 5, if the system has 1000 lines, the first connection stage will comprise 100 group connecting devices each with 10 lines (111, 211 . . . 011; 112, 212 . . . 012 etc.), forming as a second connection stage 10 group connecting stages each having 100 stations. These latter group connection stages are then united in a multiple circuit with 1000 stations as the third connection stage. The multiple circuit then extends again to a multiplex device. Since 1000 associated pulses fill in such a case an interval of 100 μ sec., the lines having pulses which are spaced by 100 pulses (not by 10 pulses as explained before) will be gathered in groups, so as to carry out the pulse expansion, i. e., as shown in Fig. 5. The groups will for example comprise the lines Tn_{111} , Tn_{211} . . . Tn_{011} , then the lines Tn_{112} , Tn_{212} . . . Tn_{012} , and so forth, each group connected with a group connecting device as the first connecting stage and the other groups correspondingly with the remaining 99 group connecting devices. The pulse duration is thereby shortened from one to the next connecting stage, i. e., from 5 μ sec. in back of the first connecting stage to 0.05 μ sec. in back of the third connecting stage at the multiplex input ME . In the direction of the desired line, that is, from the third to the first connection stage, the pulse duration will again be expanded so as to reach 5 μ sec. at the group connection device of the desired line.

Fig. 5 shows only the general wiring scheme of the individual connection stages without the required inlet and outlet gates as well as the other elements which have been already explained with reference to Figs. 2-4. In such a grouping of the subscriber lines and subdivision of the transmission channel there will appear the following advantage, due to the reduction from stage to stage of the pulse duration from 5 μ sec. to 0.5 μ sec. and then to 0.05 μ sec.:

The first connection stage which comprises a great number of group connecting devices (100) and which has due to the pulse duration of 5 μ sec. a basic frequency, e. g., of 500 kc., in view of this basic frequency does not require an excessive expenditure so far as cabling and amplification are concerned.

The second connecting stage having a lesser number of group connecting devices, which have been reduced, for example, by the factor 10, and which has due to the pulse duration of 0.5 μ sec. a higher basic frequency (5 mc.), requires in view of this higher basic frequency a greater expenditure but a lesser number of units.

The third connecting stage has due to the pulse duration of 0.05 μ sec. the highest limit frequency (about 50

mc.) and therefore requires the greatest expenditure. This is however bearable since there is only one such connecting stage.

Aside from the advantages described above, there remains of course the advantage that the damping of the transmission of the entire system is reduced by the pulse expansion at the called end of the connections.

The special expenditure so far as cabling and amplification are concerned may now be avoided in the third stage, if such stage is eliminated by forming the common transmission channel which is reached by all subscriber lines, as a selection stage. Fig. 6 which will be described next shows an example how this may be done.

The system has, as also assumed in Fig. 5, 1000 lines. Each rectangle shown at the left of Fig. 6 represents a group of 100 lines which are grouped according to the scheme shown for 100 stations in Fig. 2. The lines of the hundreds groups thus formed, namely, groups G_1 . . . G_{10} reach their respective multiplex input and output over corresponding connecting stages as shown in Fig. 2. The first hundreds group G_1 which comprises the lines Tn_{111} . . . Tn_{100} reaches the multiplex input ME_1 and output MA_1 . The second hundreds group G_2 , comprising the lines Tn_{211} . . . Tn_{200} , reaches the multiplex input ME_2 and output MA_2 . The ninth hundreds group G_9 with its lines Tn_{911} . . . Tn_{900} reaches the multiplex input ME_9 and the output MA_9 ; and the tenth hundreds group G_{10} with the lines Tn_{011} . . . Tn_{000} reaches the multiplex input ME_{10} and the output MA_{10} .

Connecting devices are wired with the multiplex input ME_1 and with the corresponding output MA_1 which correspond in number to the number of expected simultaneous calls. In the example shown in Fig. 6 there are assumed to be provided ten such connecting devices, only two of such devices VEI_1 and VEI_{10} being shown. The other side of each of these connecting devices is connected with vertical bars s_1 and s_2 of a cross-bar multiple. The multiplex input ME_1 is in addition connected with horizontal bars w_1 and the multiplex output MA_1 is similarly connected with horizontal bars w_2 . The multiplex inputs and outputs of the remaining hundreds groups are similarly connected with the cross-bar multiple. In order to connect over the crossbar multiple each line with each other line in the system, there are provided between the vertical and horizontal bars selectively operable switching means as indicated in Fig. 6 by the dots at the crossbar crossing points.

In this system, connections are built up as follows:

If a connection is to be extended from the subscriber line Tn_{111} to the line Tn_{900} , the calling line Tn_{111} , as described in connection with Fig. 2, will reach its associated group connecting device over its outlet gate (associated pulse $P_{11}=5 \mu$ sec.); from there the outlet gate of such group connecting device (pulse $P'_{11}=0.5 \mu$ sec.); and finally over the multiple circuit the multiplex input ME_1 . If the connecting device VEI_1 is idle, it will serve among other things, as explained in connection with Fig. 3, for transferring the pulse P'_{11} of the calling line to the pulse P'_{00} of the called line. The calling subscriber Tn_{111} is also connected, over the connecting device VEI_1 , to the vertical bar s_1 of the crossbar multiple which will subsequently be connected with the corresponding horizontal bar depending on the succeeding group marking of the called line, that is, depending on the first digit transmitted from the calling line. Since the subscriber's line Tn_{900} is called, i. e., the ninth hundreds group G_9 , the first series of dial pulses consisting of nine pulses, will connect the vertical bar s_1 with the horizontal bar w_6 , such switching connection being made at the corresponding crossing points of the bars. The vertical bar s_2 is at the same time connected with the horizontal bar w_5 at the corresponding crossing point indicated in Fig. 6. The multiplex input ME_1 is in this manner connected with the multiplex output MA_9 over the connecting device VEI_1 by way of the vertical bar s_1 and the horizontal bar

w_6 , and the multiplex output MA_1 is similarly connected with the multiplex input ME_1 over the connecting device VEI_1 by way of the vertical bar s_2 and the horizontal bar w_5 . The further marking of the called line by the succeeding series of dial pulses O and O (each consisting of 10 impulses) causes the connecting device VEI_1 , in the manner described in connection with Fig. 3, to transmit the pulse P'_{00a} , thereby causing the multiplex output MA_9 in the hundreds group G_9 to periodically connect the subscriber line Tn_{900} as already described in connection with Fig. 2.

When the called line Tn_{900} answers, it will be connected with the multiplex input ME_9 by the operations governed by its associated pulse $P_{00}=5 \mu\text{sec}$, as described with reference to Fig. 2. Since the multiplex input ME_9 is connected with the horizontal bar w_5 and the latter with the vertical bar s_2 , there will be established a connection with the multiplex output MA_1 by way of the connecting device VEI_1 . As explained in describing Fig. 3, the connecting device VEI_1 transforms the pulse P'_{00} into the pulse P'_{11} and the latter pulse periodically connects the line Tn_{111} with the multiplex output MA_1 over the multiplex output MA_1 in the hundreds group G_1 .

It will be seen therefore that the message outgoing from the line Tn_{111} reaches the desired line Tn_{900} from the multiplex input ME_1 over the connecting device VEI_1 and the crossbar multiple to the multiplex output MA_9 . The message in the opposite direction, from the line Tn_{900} to the line Tn_{111} is transmitted from the multiplex input ME_9 over the crossbar multiple and the connecting device VEI_1 to the multiplex output MA_1 .

If a connection is to be handled at the same time from the line Tn_{200} to the line Tn_{911} , the calling line Tn_{200} will reach the multiplex input ME_2 by means of its associated pulse P_{00} and P'_{00} , respectively. This multiplex input ME_2 is connected with an idle connecting device, e. g., $VEII_{10}$. The transmission of the first digit "9" will cause connection of the vertical bar s_7 with the horizontal bar w_6 and vertical bar s_8 with the horizontal bar w_5 . The multiplex input ME_2 is now connected with the multiplex output MA_9 and the input ME_9 with the output MA_2 . The two succeeding digits transmitted by the calling party Tn_{911} which correspond to the last two digits "1" and "1" of the called party Tn_{911} cause the connecting device $VEII_{10}$ to transmit the periodic pulse P'_{11a} which causes in the hundreds group G_9 the periodic connection of the station Tn_{911} , thus completing the call to the desired party Tn_{200} . The pulse P'_{11} is transformed into the pulse P'_{00a} in the connecting device $VEII_{10}$, for the transmission of the message in opposite direction, and the line Tn_{911} thus reaches the line Tn_{200} over the multiplex input ME_9 by way of the switching point between the vertical bar s_8 and the horizontal bar w_5 and the connecting device $VEII_{10}$.

Mutual interference between the two messages (Tn_{111}/Tn_{900} and Tn_{200}/Tn_{911}) along the common horizontal bars w_5 and w_6 does not occur because the corresponding message portions are transmitted over these bars by the pulses P'_{00} and P'_{11} , respectively, which become effective at the different instances.

It will be seen that in such a connection, the pulses serving as carriers for the modulation are shortened only to $0.5 \mu\text{sec}$, and not to $0.05 \mu\text{sec}$. as was the case in the last connecting stage of the example discussed with reference to Fig. 5, because in the example according to Fig. 6, the common transmission channel is formed in a selection stage having different switching branches over which the different messages are built up and transmitted.

The corresponding selection stage need not be formed as a crossbar multiple; the crossing points may be formed by the contacts of relay selectors having relays which are set by the group selection of the calling line and which cause the switching of the crossing points indicated responsive to such group selection.

Fig. 6a shows in diagrammatic manner an arrange-

ment as noted in the foregoing paragraph. The first impulse will for example energize the relay R_1 causing closure of contacts r_1 and r'_1 , thereby interconnecting s_1/w_4 and s_2/w_1 , respectively. The next following impulse series, e. g., digit 2, causes deenergization of relay R_1 and energization of relay R_2 , causing closure of contacts r_2 and r'_2 and therewith interconnection of s_1/w_4 and s_2/w_3 , respectively. The operations are similar for other digits and for the other interconnecting or switching points (not shown).

The switching may also be accomplished by the use of switches having wipers. Fig. 6b shows a corresponding example. The conductors s_1 and s_2 terminate, e. g., in the two wipers of a rotary switch w_1 which is set by the group selection digit of the calling line upon the contacts to which are connected the multiplex inlet and outlet of the desired hundreds group.

In place of the contacts such as r_1 and r'_1 of Fig. 6a, tubes may be provided at each crossing or switching point, e. g., tubes such as indicated in Fig. 6c or gates such as shown in Fig. 6d, which are operated by control potentials at the points S for respectively closing and opening the associated circuits. The connection extends over each contact only in one direction and no particular precaution need be taken in the use of the tubes for obtaining passage of current in both directions.

The invention is not inherently limited to telephone systems but may be used in other types of signalling systems as well. Changes may be made within the scope and spirit of the appended claims.

I claim:

1. In a telephone system having a plurality of individual subscriber stations subdivided into a plurality of groups, each group comprising a plurality of subscriber stations, a circuit arrangement for transmitting substantially simultaneously a plurality of messages carried by message-modulated pulses in accordance with a plurality of calls existing simultaneously between intercommunicating subscriber stations, said circuit arrangement comprising means for producing pulses which are respectively assigned to individual subscriber stations in each group of stations, means for periodically transmitting the respective pulses in the identical rhythm but in different time sequence, normally closed gate means cooperatively associated with subscriber stations in each group, a connecting device which is common to each group of stations, circuit means for connecting said gate means with said common group connecting device, circuit means for feeding to said gate means the pulses which are respectively assigned to the subscriber stations in the respective groups, said gate means being periodically opened by the pulses fed thereto whereby the individual stations in the corresponding groups are at different successively occurring instances operatively interconnected with said common connecting device, the spacing between said instances being a multiple of the spacing between the individual pulses, said pulses being thereby extended to the intercommunicating subscriber stations to which they are respectively assigned, for modulation thereof by portions of messages to be respectively conveyed thereby and which originate at the corresponding intercommunicating subscriber stations, a common transmission channel for all said groups, and a control circuit comprising an electron tube device which is cooperatively respectively associated with the connecting device which is common to each group, said control circuit being operatively responsive to said message-modulated pulses for interconnecting said connecting device with said common transmission channel and for simultaneously expanding said pulses.
2. The system defined in claim 1, wherein said control circuit comprises means including capacitors, inductances and rectifying means electrically coupled together so that said pulses are amplified.
3. The system defined in claim 1, wherein said control circuit comprises means including capacitors, inductances

and rectifying means electrically coupled together for successively storing the received message modulated pulses and successively releasing such pulses, the duration of storing of said pulses being determined by the duration of the corresponding received pulses, the duration of each released pulse exceeding that of the corresponding received pulse.

4. The system defined in claim 1, comprising means in said control circuit for successively storing the received message modulated pulses and successively releasing such pulses, the duration of storing of said pulses being determined by the duration of the corresponding received pulses, the duration of each released pulse exceeding that of the corresponding received pulse, valve means in the discharge circuit of said storing means, and circuit means controlled by the pulse of greater duration for blocking said valve means.

5. The system defined in claim 4, comprising means effective during the blocking interval for connecting said common connecting device over said control circuit with said common transmission channel, means forming an inlet gate associated with the line to which said pulse is assigned, means for periodically opening said gate in step with said pulse, circuit means for transmitting said received message modulated pulse over said common connecting device and said inlet gate, and means for demodulating said pulse and directing the remaining message portion carried thereby to said line.

6. The system defined in claim 4, comprising means effective during the blocking interval for connecting said common connecting device over said control circuit with said common transmission channel, means forming an inlet gate associated with the line to which said pulse is assigned, means for periodically opening said gate in step with said pulse, circuit means for amplifying and for transmitting said received message modulated pulse over said common connecting device and said inlet gate, means for demodulating said pulse, and means for amplifying the remaining message portion carried thereby and directing such portion to the corresponding line.

7. The system defined in claim 1, comprising a plurality of connecting devices for extending a calling line to said common transmission channel, and means in said devices for successively shortening said message-modulated pulses.

8. The system defined in claim 1, comprising a plurality of connecting devices for extending a calling line to said common transmission channel, and means in said devices for successively modifying said message-modulated pulses.
